DISPLAY CARTON

Strieder Schraffenberger, Millburn, N. J.

Application January 28, 1937, Serial No. 122,731

1 Claim. (Cl. 206—44)

This invention relates to cartons which are adapted to serve as shipping containers for merchandise and afterwards to be used to display the merchandise on the counter.

5 Cartons of the general type to which the present invention is directed have been proposed heretofore. In these cartons, the carton body is cut through along a line extending across its front wall and both its side walls leaving a line of fold in 10 its back wall about which one section may be swung forward relative to the other to bring the parts into positions facing in the same direction and to expose and display the merchandise. When such cartons are used as shipping containers it is necessary to insert a build-up within 15 the carton and to place a sleeve around the carton to prevent relative movement of the two sections of the carton. It also has been necessary to provide some means for effectively holding the 20 two sections together while in display position.

It is an object of the present invention to provide a carton of this general type which is so constructed that the use of inside build-ups and exterior sleeves when the carton is serving as a shipping container is unnecessary.

It is another object of the invention to provide a carton construction such that the two sections may be swung into their display positions and maintained in such positions without special provisions for maintaining them in such positions.

The invention will be more clearly understood from the following description in conjunction with the accompanying drawing: in which,

Fig. 1 illustrates a blank adapted to be folded to 35 provide a carton embodying the invention;

Fig. 2 is a perspective view of a carton embodying the invention; and

Fig. 3 is a perspective view showing the two portions of the carton in their display positions.

40 Before explaining in detail the present invention it is to be understood that the invention is not limited in its application to the details of construction and arrangement of parts illustrated in the accompanying drawing, since the invention is 45 capable of other embodiments and of being practiced or carried out in various ways. Also it is to be understood that the phraseology or terminology employed herein is for the purpose of description and not of limitation, and it is not intended to 50 limit the invention claimed herein beyond the requirements of the prior art.

In Fig. 1 of the accompanying drawing, there is illustrated a blank which is shaped and scored so that it may be folded to provide portions which 55 form the front, back and side walls and the end

closures of the carton. The portions 10 and 11 provide the carton side walls and the portions 12 and 13 provide the front and back walls. A portion 14 extends from the side edge of the portion 13 and is adapted to engage and be secured to the inner surface of the portion 10 when the blank is folded to form the carton. The blank is also provided with pairs of notched tabs 17 and 18 at opposite ends of the carton adapted to extend across the end opening of the carton and be interlocked. The portions 19 and 20 of the blank 10 form the carton end closures.

The portion 14 of the blank is provided with a line of cut 15 and the portion 10 is provided with a median crease line 16 extending transversely 15 thereacross. The cut 15 is adapted to coincide with the crease line 16 when the blank is folded to form the carton. A division line 25 extends across the walls 11, 12 and 13 and has a U-shaped portion 26 and an inverted U-shaped portion 27 located in the walls 12 and 13 respectively. The division line 25 is so positioned as to extend from opposite ends of the crease line 16 when the blank is folded to form a carton. Preferably, the division line 25 is formed by a series of aligned longitudinally spaced cuts 28 through the carton walls so as to leave uncut portions 29 between the ends of the cuts.

The division line 25 defines two carton portions 30 and 31. Hinging of the carton portions 30 and 31 about the crease line 16 is prevented by the uncut portions 29 of the division line 25 which serve to hold the carton portions together when the carton is serving as a shipping container and, consequently, the use of inside build-ups and a sleeve to hold the carton together is unnecessary. The carton portions 30 and 31 may be readily divided by severing the uncut portions 29 of the division line 25 so as to permit the carton portions 30 and 31 to hinge into their display positions facing in opposite directions and with a side wall of one adjacent a side wall of the other, as shown in Fig. 3.

It will be noted that the U-shaped portion 26 and inverted U-shaped portion 27 of the division 45 line 25 divide the front and back walls of the carton so as to provide an upwardly extending projection 33 on the back wall of each of the oppositely facing portions 30 and 31 when in their display positions and to provide a cut away portion 34 in the front wall of each of the carton portions 30 and 31 when in their display positions as shown in Fig. 3. Inasmuch as the carton portions 30 and 31 are swung about a median crease line 16 in one of the side walls of the carton to bring them into 55

their display position, the carton portions 30 and 31 are maintained in their display position solely by their own weight. It will also be noted that the blank may be printed on both sides with advertising matter so that the latter will be in view of customers upon each of the oppositely facing display portions 30 and 31 of the carton.

What I claim is:

A shipping carton convertible to form a pair of display containers comprising a body having front, back and side walls and end closures, one of said side walls having a median crease line connecting the front and back walls, the other of said side walls and said front and back walls having a continuous division line extending across the same and connecting opposite ends of said crease line, said division line extending across said other side

wall midway between its ends, the portions of said division line upon said front and back walls each defining a U-shaped margin located at one end of one wall and at the opposite end of the other wall, said division line being readily severable to form two carton portions connected by said crease line and adapted to hinge about said crease line to provide two similarly shaped oppositely facing display containers positioned side by side with the front wall of each aligned with the back wall of the other and with their bottoms lying in a common plane and formed by said end closures, each of said containers having a cut-away front wall formed by one of said U-shaped margins and having a back wall which is complementary to its front wall.

STRIEDER SCHRAFFENBERGER.
